UNITED STATES PATENT OFFICE.

EDWIN E. THOMAS, OF TACOMA, WASHINGTON, ASSIGNOR TO WIL-
LAMETTE IRON & STEEL WORKS, OF PORTLAND, OREGON, A
CORPORATION.

LOG-TURNER FOR LOW MILLS.

SPECIFICATION forming part of Letters Patent No. 773,437, dated October 25, 1904.

Application filed October 10, 1903. Serial No. 176,473. (No model.)

To all whom it may concern:

Be it known that I, EDWIN E. THOMAS, of Tacoma, county of Pierce, State of Washington, have invented certain new and useful Im-
5 provements in Log-Turners for Low Mills, of which the following is a specification.

In sawmills as usually constructed an ex-
cavation is provided beneath the log-carriage
and the front of the log-deck, forming a base-
10 ment wherein the mechanism for operating a
steam log loader and turner is placed. It is
frequently difficult or undesirable to provide
a basement for a mill, owing sometimes to
the character of the ground where the mill is
15 located; and the primary object, therefore, of
my invention is to provide an apparatus for
operating the log-turner which can be placed
in a ground-mill or one without any excava-
tion under it, but can also be used in a two-
20 story mill, if desired.

The invention consists generally in various
constructions and combinations, all as herein-
after described, and particularly pointed out in
the claims.

25 In the accompanying drawing, forming
part of this specification, the figure represents
a side elevation of a log-turning apparatus
embodying my invention.

In the drawing, 2 represents a log-deck,
30 and 3 the carriage, supported upon a suitable
track 4 in front of the deck.

5 is an engine-cylinder horizontally ar-
ranged upon a timber 6 beneath the log-deck
and provided with a suitable valve mechan-
ism 7, by means of which the flow of steam
35 into the cylinder is controlled. The piston 8
of the cylinder 5 is connected with a sliding
cross-head 9, also supported upon the timber
6, and said cross-head is pivotally connected
40 to a bar 10, to which a slightly-curved bar 11
is secured and provided with a series of teeth
12, mounted therein in the usual manner and
adapted to engage the surface of the log when
the bar 11 is raised above the level of the log-
45 deck. A suitable brace 13 connects the bars 10
and 11. Beneath the cylinder 5 is a second cyl-
inder 14, having a valve 14' and supported on a

timber 15 and having its piston connected
with a sliding cross-head 17, also supported on
said timber. A bell-crank 18 is pivoted on a 50
timber 19 and is pivotally connected to said
cross-head and to one end of a link 20, whose
opposite end is secured to the bar 13 near its
upper end.

The operation of the device is as follows: 55
Steam being admitted to the cylinders, the
frame composed of the bars 10, 11, and 13
will be oscillated on its pivot and swung to
a position above the log-deck, and the teeth
12 engaging the surface of the log will turn 60
it to the desired position.

It will be noted that the apparatus is very
compact in form and occupies but little space
beneath the log-deck and being arranged
horizontally does away entirely with the ne- 65
cessity of excavating a basement beneath the
mill.

I claim as my invention—

1. The combination, with a log-deck and car-
riage, of the engine-cylinders horizontally ar-
ranged beneath the same, sliding cross-heads
whereto said cylinder-pistons are connected,
a log-turner frame pivoted on one of said
cross-heads and having a series of teeth adapt-
ed to engage the surface of a log, a bell-crank 75
pivotally connected with the other cross-head,
and a link pivotally connecting said bell-crank
and said log-turner frame.

2. The combination, with a log-deck, of
engine-cylinders horizontally arranged one 80
above the other below said deck, cross-heads
whereto the pistons of said cylinders are con-
nected, a log-turner frame pivoted to the
cross-head of the upper engine and having a
series of teeth arranged to be projected above 85
the log-deck, a bell-crank pivotally supported
between said cross-heads and having a pivotal
connection with the lower one, and a link piv-
otally connecting said bell-crank with said
log-turner frame.

3. A log-turning device for low mills, com-
prising in combination, a frame arranged be-
neath the log-deck and having a series of log-
turning teeth, a fluid-motor horizontally ar-

ranged below the log-deck and having its piston pivotally connected with said frame to operate the same horizontally, a second fluid-motor also horizontally arranged below said first-named motor, and a bell-crank mechanism connecting the piston of said second motor and said frame to operate the same vertically.

4. The combination, with a log-deck, of 10 engine-cylinders horizontally arranged one above the other beneath said deck, a log-turner pivotally connected at one end to the piston of the upper cylinder and having a series of log-turning teeth at its other end, said log-turner being normally horizontal and adapted 15 to be moved toward or from the carriage by the action of said upper cylinder-piston, and a mechanism interposed between said log-turner and the piston of said lower engine and 20 adapted to move said turner vertically against

the log when the horizontal movement of said turner toward the carriage is completed.

5. A log-turning device for low mills comprising, in combination, a frame having a series of log-turning teeth, an engine horizontally arranged and having its piston pivotally connected with said frame to operate the same horizontally, a second engine also horizontally arranged, and a mechanism interposed 25 between said frame and the piston of said second engine and adapted to move said frame and teeth vertically against the log when the horizontal movement of said frame is completed, substantially as described.

In witness whereof I have hereunto set my 35 hand this 29th day of September, 1903.

EDWIN E. THOMAS.

In presence of—

HERBERT S. GRIGGS,
E. G. CONNICK.
